UNITED STATES PATENT OFFICE.

WILLIAM ARNOLD MATHER AND JAMES SMITHIES, OF WILMSLOW, NEAR MANCHESTER, ENGLAND, ASSIGNEES TO FAIRE BROS. & CO. LIMITED, OF LEICESTER, ENGLAND.

STRING AND LIKE FASTENER.

Application filed October 4, 1921. Serial No. 505,295.

To all whom it may concern:

Be it known that we, WILLIAM ARNOLD MATHER, of The Rowans, Hawthorn Lane, Wilmslow, near Manchester, in the county 5 of Lancaster, England, and JAMES SMITHIES, also of Wilmslow, near Manchester, in the county of Lancaster, England, subjects of the King of Great Britain and Ireland, have invented certain new and useful Improvements 10 Relating to String and Like Fasteners, of which the following is a specification.

This invention has for its object the production of improved string and like fasteners for the tying or binding together of 15 leaves or papers, for closing the mouths of bags or like receptacles and for other services.

The invention comprises the arrangement and combination of parts as hereinafter particularly described and as illustrated in the 20 accompanying explanatory drawings.

Referring to the said drawings:—

Figure 1 illustrates a fastening device suitable for closing the mouth of a bag or 25 securing a roll or bundle of papers or other articles.

Figure 2 shows the improved fastening device combined with a stiffener or support for papers, whilst Figure 3 gives an example 30 of a slip noose type of fastening made in accordance with this invention.

The same reference letters in the different views indicate the same or similar parts.

The improved device consists of a single 35 length of cord or tape *a*, the two ends of which are threaded through one or more india rubber washers *d* in opposite directions, as shown. Knots *e* may be tied at the ends

of the strings or the like to form abutments which prevent the said ends being pulled 40 through the washers. The papers or the like to be bound are placed in the loop made by the washer or washers on the cord and the washers are adjusted in position till the cord grips the papers. The washers remain 45 securely in such position, due to their binding upon the cords. Pulling upon the ends of the cord ensures the readjustment of the position of the washers.

The binding device may be used alone or 50 may be secured upon a flat cardboard *f* or similar stiffener, as in Figure 2, to carry or support flat papers, or around the mouth of a bag or other receptacle, according to the service for which it is required. In the arrangement shown in Figure 3, the string is 55 looped around an article or articles and binds against the washers. The device forms a noose which is tightened in a manner similar to that previously described and is useful 60 when it is impossible to pass the loop over the end of the article to be held.

We claim:

1. In string and like fasteners, in combination, a looped cord, a resilient grip washer, 65 the ends of said cord being threaded through the washer in opposite directions, and abutments at the cord ends, as set forth.

2. In string and like fasteners as claimed in claim 1, a stiffener within the looped cord, 70 as set forth.

In testimony whereof we have signed our names to this specification.

WILLIAM ARNOLD MATHER.
JAMES SMITHIES.
